[57] CLAIM

The ornamental design for a casino utility bag, as shown and described.

DESCRIPTION

FIG. 1 is a front view of the casino utility bag showing my new design;

FIG. 2 is a rear view thereof;

FIG. 3 is a top plan view thereof;

FIG. 4 is a bottom view thereof;

FIG. 5 is a side elevational view thereof taken from the right side of FIG. 1;

FIG. 6 is a side elevational view thereof taken from the right side of FIG. 2; and,

FIG. 7 is a perspective view thereof.

The broken line showing of a billfold in FIG. 1, 3, 5, 6 and 7 is for illustrative purposes only and forms no part of the claimed design.
